UNITED STATES PATENT OFFICE.

FREDERICK HACHMANN, OF ST. LOUIS, MISSOURI, ASSIGNOR OF ONE-HALF TO FRED C. SCHOENTHALER, OF ST. LOUIS, MISSOURI.

BOTTLE-CLOSURE.

1,214,026.

Specification of Letters Patent. Patented Jan. 30, 1917.

Application filed April 10, 1915. Serial No. 20,529.

To all whom it may concern:

Be it known that I, FREDERICK HACHMANN, a citizen of the United States, and residing at St. Louis, in the State of Missouri, have invented a certain new and useful Improvement in Bottle-Closures, of which the following is a specification.

This invention relates to closures, and more particularly, to closures for milk bottles.

One of the objects of this invention is to provide a device of this kind which may be detachably mounted on the neck of a bottle to form a movable sanitary closure therefor.

Another object is to provide a device of this kind which is simple in construction, consists of a few stamped parts, and is cheap to manufacture.

Further objects will appear from the detailed description taken in connection with the accompanying drawings, in which:

Figure 1 is a plan of a part of a bottle, showing the closure embodying this invention; Fig. 2 is a section on the line 2—2. Fig. 25 1; Fig. 3 is an end elevation, partly in section; Fig. 4 is a section on the line 4—4, Fig. 2, parts being shown in elevation; Fig. 5 is a plan similar to Fig. 1, but showing another embodiment of this invention; Fig. 6 is a 30 section on the line 6—6, Fig. 5; Fig. 7 is an end elevation; and, Fig. 8 is a section on the line 8—8, Fig. 6, parts being shown in elevation.

Referring to the accompanying drawings, 35 and more particularly, to Figs. 1 to 4 inclusive, 10 designates the neck of a bottle having the usual bead 11 at its mouth, and the usual wafer receiving recess 12. A support comprising a pair of jaws 13 and 14 formed 40 of springy material is adapted to embrace and yieldingly clamp the edge of the bottle neck. The end 15 of the jaw flares outwardly, and this jaw conforms to the inside of the bottle and follows the recess 12, as shown in Fig. 2. The outside jaw 13 conforms to the bead 11, and this jaw terminates in a part 16 of beaded form extending circumferentially partly around the bottle neck, and arranged underneath the bead 11. The 45 jaw 13 has formed integral therewith lugs 17, which are bent from the body of the jaw away from the bottle, and then laterally to form pintles 18.

A cap or closure member 19, formed of 50 sheet metal, has a rim 20 formed to engage

the rounded edge of the bottle neck, and is provided with an arm 21 having formed thereon ears 22 which are perforated to engage the pintles 18. A spring 24 is looped around the pintles inside of the ears, and the center of this spring bears against the arm or handle 21, while the ends bear against the jaw 13. The end of the arm or handle is pointed or sharpened, as shown at 25, and the arm 21 is struck up, as shown at 26, 65 where it crosses the support, so as to clear the same. This struck up portion merges into a rib 27, which extends along the handle and terminates near the point 25.

In the construction shown in Figs. 5 to 8 70 inclusive, the support again comprises a pair of jaws 13 and 14 embracing and clamping the edge of a bottle neck, but, in this case, the outside jaw flares outwardly at its end, as shown at 150, while the inside jaw terminates in a widened part 160 extending circumferentially of the bottle neck, and along the depression or shoulder 12, as shown in Figs. 6 and 8. The construction is otherwise the same as shown in Figs. 1 to 4 inclusive, 80 and further description will, therefore, be unnecessary.

Milk bottles are usually provided with paper caps or wafers held in the depression in the mouth of the bottle. In using this 85 device, this wafer is removed by inserting the point or prong 25 therethrough and extracting it. The resilient support is now slipped over the edge of the bottle, as shown in Fig. 2. This will cause the jaws to 90 firmly clamp the bottle neck, and, moreover, since the jaw on one side engages the bottle wall at substantially a point, while the jaw on the other wall engages the same at two separated points, there is obtained, in this 95 way, a three point bearing which will firmly hold the support in position on the bottle neck. The cap or closure member is now held down on the bottle by its spring, and the flange part of the cap will conform to 100 the bead so as to tightly close the same. The cap can readily be raised by a manipulation of the handle.

It will be noted that the device consists 105 only of two stamped pieces, so that it is very simple in construction and cheap to manufacture. Both parts can be made of resilient aluminum, so that the device will be entirely sanitary. Since the cap tightly closes the end of the bottle, and since it is centered on 110

the bottle neck by the engagement of the rounded recess with the rounded edge of the bottle neck, and by the entrance of the depression inside of the bottle, the end of the 5 bottle will be covered, so as to prevent the accumulation of milk, etc., in the bottle mouth around the edges thereof.

It is obvious that various changes may be 10 made in the details of the construction without departing from the spirit of this invention. It is, therefore, to be understood that this invention is not to be limited to the specific construction shown and described.

Having thus described the invention what 15 is claimed is:

1. A bottle closure comprising a support 20 consisting of a pair of spaced jaws adapted to seat downwardly over and embrace and yieldingly clamp the edge of a bottle neck 25 for removably holding the closure on the bottle, one of said jaws having a laterally projecting part extending circumferentially of and partially around the bottle neck, said support having radially projecting lugs 30 struck directly from the body of said support within the surface plane thereof and forming pintles, and a cap constructed and arranged to seat directly upon and to be self centering on the mouth of said bottle and having a downwardly directed handle provided with provided with integral inwardly directed

ears formed for engagement with said pintles to pivotally sustain said cap on said support.

2. A bottle closure comprising a support 35 consisting of a pair of spaced jaws adapted to seat downwardly over and embrace and yieldingly clamp the edge of a bottle neck having an inner circumferential shoulder, 40 said jaws being constructed and arranged for removably holding the support on the bottle and the inner jaw being adapted to project downward into the neck and having a shoulder formed to fit and seat securely on said circumferential shoulder, the outer jaw 45 being provided with a laterally projecting part extending circumferentially of and partially around the bottle neck, said support having radially projecting lugs struck directly from the body of said support within 50 the surface plane thereof and forming pintles, and a cap constructed and arranged to seat directly upon and to be self centering on the mouth of said bottle and having a downwardly directed handle provided with 55 integral inwardly directed ears formed for engagement with said pintles to pivotally sustain said cap on said support.

In testimony whereof I affix my signature this 23d day of March, 1915.

FREDERICK HACHMANN.
